ATTORNEY

UNITED STATES PATENT OFFICE.

ALBERT H. STEBBINS, OF LOS ANGELES, CALIFORNIA.

CONCENTRATOR.

Application filed July 13, 1922. Serial No. 574,600.

To all whom it may concern:

Be it known that I, ALBERT H. STEBBINS, a citizen of the United States, residing at Los Angeles, in the county of Los Angeles 5 and State of California, have invented an Improvement in Concentrators, of which the following description, in connection with the accompanying drawings, is a specification, like characters on the drawings representing 10 like parts.

This invention relates to a centrifugal concentrator or separator for separating materials in accordance with their differences in specific gravity.

15 In the concentration of ores, and in the treatment of other materials, it is often desirable to separate the materials in accordance with their differences in specific gravity irrespective of the differences in 20 the size of the particles being treated.

The present invention contemplates the separation of materials by imparting momentum to the particles, preferably by centrifugal force, and by directing a blast of 25 air against the traveling particles so that the light particles will be deflected from their path of travel to a greater extent than the heavy particles. The velocity of the particles and the resulting momentum serves 30 to accentuate the differences in specific gravity and thereby facilitates the separating operation.

An important feature of the present invention therefore resides in a combined distributor and centrifugal fan by which the 35 materials to be treated are thrown outwardly and a blast of air is forced by the fan against the materials to deflect the lighter particles away from the heavier particles.

40 Another feature of the invention resides in means for supporting in different positions of adjustment a wall which surrounds the combined distributor and fan and over which the lighter materials are deflected.

45 Other features of the invention and novel combination of parts in addition to the above will be hereinafter described in connection with the accompanying drawings which illustrate one good practical form 50 thereof.

In the drawings:

Fig. 1 is a vertical sectional view through a concentrator constructed in accordance with the present invention;

55 Fig. 2 is a sectional view taken on the line 2-2 of Fig. 1;

Fig. 3 is an enlarged sectional view through a portion of the combined distributor and fan;

Fig. 4 is a perspective view of a portion of 60 the inner casing; and

Fig. 5 is a side view of means for supporting the upper portion of the inner casing in different positions of adjustment.

The concentrator of the present invention 65 has a casing 10 conveniently constructed of sheet metal, and the lower portion of the casing is provided with a cone shaped portion 11 while the upper portion of the casing is closed by a cover 12. 70

Within the casing 10 is rotatably supported the combined distributor and fan 13, and in the construction shown the same is secured to and is rotated by a shaft 14 extending downwardly through a sleeve 15 75 supported by the cover 12. The shaft 14 is hollow as shown for the passage of air downwardly to the fan and the shaft may be driven by a pulley 16.

The combined distributor and fan 13, in 80 the construction shown, consists of three disks or plates 17, 18 and 19, secured together in spaced relation. The upper plate 17 comprises the distributor and the second plate 18 serves to form an air chamber between it and the plate 17, and the plate 18 is constructed and arranged to form an annular slot 18^a about the periphery of the distributor 17 through which a blast of air is directed against the 90 materials as they travel outwardly from the distributor. Air enters the chamber between the plates 17 and 18 through the hollow shaft 14, and ribs or vanes 20 are provided between these plates. The construction of the combined plates 17 and 18 and the interposed vanes 20 is such that they form a centrifugal fan which serves 95 upon rotation to throw the air outwardly from the chamber between the plates 100 through the annular slot 18^a. The outer ends of the vanes 20 preferably are inclined rearwardly as shown to assist in throwing or forcing the air within the chamber outwardly through the slot 18^a. 105

These vanes support the plates 17 and 18 in spaced relation and are secured in place by rivets 21.

In the construction shown the plate 19 serves to form a second chamber having an 110 annular slot 19^a about the distributor 17 through which a blast of air is directed,

further to subject the materials thrown outwardly by the distributor to a deflecting blast of air. It is not necessary, however, in all embodiments of the invention to provide 5 more than one annular slot for directing air against the materials thrown outwardly by the distributor. The chamber between the plates 18 and 19 has vanes 22 therein which may be similar in construction and operation 10 to the vanes 20. Air is drawn into the chamber between the plates 18 and 19 through the opening 23 at the center of the plate 19, and is forced outwardly through the slot 19^a, and the size of the opening 23 may be varied 15 by providing a threaded stem 24 extending downwardly from the plate 18 and carrying a disk 25 that may be adjusted toward and from the opening.

The casing 10 has an annular wall 26 20 therein which surrounds the combined distributor and fan 13 and forms an inner and outer chamber within the casing 10. The materials to be treated may be delivered upon the distributor 17 near the center thereof by a hopper 27 extending downwardly through the cover 12.

In operation, rotation of the combined distributor and fan will throw the materials upon the distributor 17 outwardly by 30 centrifugal force toward the wall 26, and the rotating vanes 20 and 22 will serve to throw the air within the chambers outwardly through the annular slots 18^a and 19^a in the form of blasts to deflect the lighter materials 35 from their path of travel and over the wall 26. The heavier particles that are not lifted by the blasts of air sufficiently to clear the wall 26 slide down the wall into the lower casing 28 and pass out of this casing 40 through the pipe 29. The lighter particles that pass over the top of the wall 26 move downwardly within the outer chamber and slide down the cone shaped wall 11 into a discharge pipe 30.

45 It may be desirable to vary the operation of the present concentrator by raising or lowering the wall 26 relative to the distributor 17, and to this end, in the present case, the wall 26 is provided at its lower end with 50 a cylindrical portion 31 that fits frictionally within the casing 28, and this wall is conveniently supported in different positions of adjustment by providing the upper edge of the casing 28 with inclined surfaces 32 upon 55 which blocks 33 secured to the sides of the cylinder portion 31 may rest. As a result of this construction, rotation of the wall 26 in one direction will raise this wall and rotation in the opposite direction will lower this 60 wall, and the frictional engagement of the portion 31 with the casing 28 may be sufficient to prevent accidental movement.

Air may be supplied to the opening 23 of 65 the lower fan by a pipe 34 extending upwardly within the inner chamber of the cas-

ing 10, and a sliding gate 35 may serve to regulate the flow of air upwardly through this pipe. Most of the air thrown outwardly through the annular slots 18^a and 19^a will move outwardly into the outer chamber, and 70 this air may escape therefrom through a pipe 36 leading from the material discharge pipe 30. Air is prevented from escaping through the material discharge pipes 29 and 30 by causing these pipes to empty into 75 closed receptacles 37 and 38.

In some cases it may be desirable to produce a blast of air through the annular slot 18^a that is stronger than will be produced by the rotating vanes 20. In this case the 80 upper end of the hollow shaft 14 may have a pipe 39 connected thereto and the pipe 39 may lead from any desired source of air pressure.

By providing a combined distributor and fan, as herein described, it is unnecessary to provide means external of the casing for compressing air and forcing it into the concentrator, and as a result, the present concentrator is simple in construction, is self-contained and consists of but few parts.

What is claimed is:

1. An air concentrator, comprising in combination, a combined rotary distributor and centrifugal fan, consisting of a distributing plate and a second plate supported in close proximity to the distributing plate to form a fan chamber therebetween and having a restricted annular discharge slot between the outer peripheral portions of the two plates, ribs between the plates forming fan blades, means for delivering materials to be treated to the distributor to be thrown outwardly thereby, a wall surrounding the distributor in spaced relation thereto, and means for rotating the combined distributor and fan to throw the materials outwardly and to force currents of air produced by the fan through said restricted discharge slot in the form of a blast directed against the outwardly thrown materials to deflect the lighter materials from the wall.

2. An air concentrator, comprising in combination, a rotary distributor having a disk adapted to throw outwardly materials delivered upon the upper face of the disk, a wall surrounding the distributor in spaced relation thereto, fan vanes secured to the lower face of the disk to throw air outwardly, and means having a surface inclined 115 to the path traveled by the materials thrown outwardly by the distributor and adapted to direct the air in an inclined direction toward the material to deflect the lighter materials from the wall.

3. An air concentrator, comprising in combination, a combined rotary distributor and centrifugal fan, including a disk adapted to throw outwardly materials delivered upon its upper face, a second disk spaced 120

- from the first to form an air chamber between the disks and the disks having their peripheral portions disposed to form a restricted annular discharge slot, fan blades 5 between the disks for forcing air outwardly through the restricted discharge slot in the form of a blast directed at an inclination against materials leaving the distributor to deflect the lighter materials to a greater extent than the heavier materials, and a wall 10 surrounding the distributor to divide the materials in accordance with the deflection thereof.
4. An air concentrator, comprising in combination, a combined rotary distributor and centrifugal fan, including a disk adapted to throw outwardly materials delivered upon its upper face, a plate positioned in spaced relation to the disk to form an air 15 chamber therebetween having a peripheral portion disposed to form a restricted annular discharge slot about the periphery of the disk, and fan vanes within the chamber for forcing air outwardly through the restricted 20 slot in an inclined direction against materials leaving the distributor to deflect the lighter materials to a greater extent than the heavier materials, and a wall surrounding the distributor to divide the materials in 25 accordance with the degree they are deflected by the air.
5. An air concentrator comprising in combination, a combined rotary distributor and centrifugal fan, including a disk adapted 30 to throw outwardly materials delivered upon its upper face, two plates secured to the disk in spaced relation and forming air chambers having annular discharge slots about the periphery of the disk, and fan 35 vanes in said chambers for throwing air outwardly against materials leaving the distributor to deflect the lighter materials to a greater extent than the heavier materials,
- and a wall supported in spaced relation to the distributor to divide the materials in accordance with the degree they are deflected by the air.
6. An air concentrator, comprising in combination, a combined rotary distributor and centrifugal fan, including a pair of spaced plates having vanes between them forming fan blades and one plate constructed to form a distributor, said plates being constructed to form a restricted annular discharge slot surrounding the vanes 55 and adapted to direct air against the materials leaving the distributor, means for rotating the combined distributor and fan to throw the materials outwardly and to force air outwardly through the restricted slot 60 against the materials to deflect the lighter materials, and a wall positioned so that some of the materials will be deflected over it while others will not.
7. An air concentrator, comprising in combination, a combined rotary distributor and centrifugal fan, including a rotatable distributing plate upon which the materials are delivered, and a fan casing secured to the distributing plate to rotate therewith 70 and having a peripheral portion disposed to form a restricted annular discharge slot at the periphery of the plate, fan vanes within the space between the casing and plate for forcing air outwardly through the 75 restricted slot against the materials thrown outwardly by the distributor to deflect the lighter materials, a wall positioned so that some of the materials will be deflected over it while others will not, and means for relatively adjusting the distributor and wall 80 to vary the separation of the materials.

In testimony whereof, I have signed my name to this specification.

ALBERT H. STEBBINS.
